CLAIM

(51) LOC (14) Cl. **14-04**

The ornamental design for a display screen with graphical user interface with an icon, as shown and described.

(52) U.S. Cl.

USPC **D14/492**

DESCRIPTION

(58) **Field of Classification Search**

The file of this patent contains at least one drawing/photograph executed in color. Copies of this patent with color drawing(s)/photograph(s) will be provided by the Office upon request and payment of the necessary fee.

USPC ..... D14/489—495, 485—488
CPC G06F 3/0482; G06F 3/048; G06F 3/04842;
G06F 3/04845; G06F 3/0481; G06F
3/04817; H04M 1/724—72484

The FIGURE is a front view of a display screen with graphical user interface with an icon.

See application file for complete search history.

The outermost broken-line rectangle illustrates a display screen and forms no part of the claimed design. The remaining broken-lines illustrate portions of a graphical user interface and form no part of the claimed design.
